(57) **CLAIM**

The ornamental design for a lamp, as shown and described.

DESCRIPTION

1. Lamp
- 1.1 : Perspective
- 1.2 : Perspective
- 1.3 : Front
- 1.4 : Left
- 1.5 : Top
- 1.6 : Right
- 1.7 : Bottom
- 1.8 : Left
- 1.9 : Cross-sectional

The break lines in the drawings indicate that the appearance of any portion of the lamp between the break lines forms no part of the claimed design;

Figure 1.9 shows a section cut along plane 1.9-1.9 of Figure 1.8 in order to show the outer contour of the cross section of the lamp.
